UNITED STATES PATENT OFFICE.

CHARLES HEMJE, OF WASHINGTON, DISTRICT OF COLUMBIA, ASSIGNOR OF
ONE-HALF TO CHRISTIAN ABNER, OF SAME PLACE.

METALLIC BUSHING.

SPECIFICATION forming part of Letters Patent No. 289,654, dated December 4, 1883.

Application filed October 31, 1883. (No model.)

To all whom it may concern:

Be it known that I, CHARLES HEMJE, a citizen of the United States, residing at Washington, in the District of Columbia, have invented certain new and useful Improvements 5 in Metallic Bushings; and I do hereby declare the following to be a full, clear, and exact description of the invention, such as will enable others skilled in the art to which it applies to make and use the same.

This invention relates to metallic or rigid bushings for barrels, kegs, &c., and especially to that kind in which wooden plugs are used, said plugs being provided with a suitable cavity 15 for the introduction of the spigot into the cavity, so that after the web of the plug has been removed the remaining portion of the plug forms a yielding lining in the rigid bushing. One great objection in the bushings now 20 in use is that the web of the plug, which has been compressed so as to give the plug a tapering shape, has a tendency to swell again to its normal size as soon as the liquid contained in the keg or barrel comes in contact with it, 25 in consequence of which the web is held much more firmly by the bushing than the ring of the plug, for which reason it frequently happens that the web does not split from the ring, as is intended, but carries the ring with it into 30 the keg, thus spilling more or less of the contents.

The object of my invention is that the web of the plug shall not be held any firmer than any other portion of it, or, if anything, shall 35 not be held as firmly, so as to prevent the ring of the plug from being driven through the bushing; and, furthermore, by a peculiar construction of the interior of the bushing, a cut or groove is made in the exterior circumference 40 of the plug at a point where the split is intended to take place, so that the web can be removed from the ring at a certain point.

In the accompanying drawings, Figure 1 represents a vertical section of my improved 45 bushing. Fig. 2 is a plan view of the same. Fig. 3 is a bottom view, and Figs. 4 and 5 are modifications of Fig. 3. Fig. 6 is a central sectional view of the form of bung or plug used with my improved bushing.

50 The bushing is slightly tapering, as shown in Figs. 1 and 2. On its outer circumference

it is provided with screw-threads, for the purpose of fastening it into the head of the keg or barrel, and at the top it is provided with a flange, A, which rests on the head of the keg, 55 or can be sunk into the head so as to be flush. The interior of the bushing is also slightly tapering, so as to conform to the taper of the wooden plug E, to be used in the same, and at its inner or smaller end is provided with a series 60 of recesses, c c' c'', said recesses being in height from the lower or smaller end about equal to the thickness of the web of the plug. These recesses, as shown in Figs. 1 and 3, form between them an equal number of projections or 65 shoulders, d d' d''. The object of these recesses is that the web or solid portion of the plug shall not be held so firmly, as is the case in the present bushings, where it is held circumferentially, but is only held by the shoulders or projections 70 75 d d' d'', at the same time allowing the liquid to enter the recesses, so that the web of the plug can partially expand, causing the projections or shoulders to embed themselves more firmly into the web, while the upper nearly right-angled corners of the recesses also embed themselves into the outer circumference of the plug, because, while the web of the plug has a chance to expand into the recesses, the ring of the plug cannot expand, as it rests solidly against 80 the upper or smooth portion of the bushing, thus forming an indentation or cut, which assists the web to split from the ring of the plug at the desired point. It will be clearly understood that if the web of the plug is held only 85 by projections d d' d'', which form, as in the drawings shown, only about one-third of the circumference, it will only take about one-third of the power to drive it through the lower end of the bushing as compared with a bushing 90 which holds the web circumferentially. By increasing or decreasing the width of the shoulders d d' d'', the pressure against the web of the plug is either increased or decreased, which pressure can therefore be regulated so that the 95 ring of the plug is held more firmly than the web, and if such is the case the web will split easily from the ring and prevent the latter from being driven into the keg also. In Fig. 3 the recesses and shoulders are right-angled, 100 or nearly so; but in Fig. 4 the shoulders only are thus, while the corners of the recesses are

rounded, to prevent dirt, &c., from collecting in the corners. In Fig. 5 the shoulders are also rounded, as well as the vertical inner corners of the recesses, thus forming a continuous 5 wave-line.

Having thus fully described my invention, what I claim as new is—

1. A bushing for barrels, kegs, or other vessels, having at its lower or smaller end a series of internal projections and intervening 10 recesses, substantially as described.

2. A bushing for barrels, kegs, or other vessels, having at its lower or smaller end a series of internal round-cornered recesses and

shoulders, substantially as and for the purpose described.

3. The combination of a bushing having a series of internal recesses and shoulders at its lower or smaller end and a plug or bung inserted therein, substantially as shown and described.

In testimony whereof I have affixed my signature in presence of two witnesses.

CHARLES HEMJE.
